ABSTRACT OF THE DISCLOSURE

Fluid logic apparatus performing binary addition comprises three mutually perpendicular jet paths respectively representing the binary values of the two digits to be added and any "carry" to be taken into account. The paths are directed to a common point and produce an output jet therefrom whose direction depends on the particular combination of input jets existing at the time. Output channels are respectively aligned with all possible directions of the output jet. Some output channels discharge into a first common channel producing the "sum" output of the addition and some of the output channels discharged into a second common channel producing the "carry" result of the addition.

The invention relates to data processing apparatus and to fluid logic elements for such apparatus.

According to one aspect of the invention, there is provided a fluid logic element, including means for directing input fluid jets towards a single point in space in respectively different predetermined inward directions which do not all lie in the same plane, whereby to produce an output fluid jet directed away from said point in an outward direction which depends on the particular combination of said input fluid jets existing at any time.

According to another aspect of the invention, there is provided a fluid logic element, comprising means for producing any one of all possible combinations of at least three input fluid jets directed towards a single point in respectively different directions so that the direction of at least one input fluid jet is transverse to a plane including at least two other said input fluid jets whereby to produce a resultant output fluid jet directed away from the said single point in a direction which depends on the particular combination of input fluid jets existing at the time, and a plurality of output channels each arranged for receiving a said output fluid jet having a respective one of the said directions.

According to a further aspect of the invention, there is provided fluid logic apparatus for performing a binary addition of two binary digits each of which can have either one of two binary values, comprising means for directing any particular combination of first, second, and third mutually perpendicular input fluid jets to a single point whereby to produce an output fluid jet directed away from the single point in a direction which depends on the particular said combination of the input fluid jets which exists at the time, presence of each said fluid jet representing one binary value and absence of each said fluid jet representing the other said binary value, the binary value of one said digit being represented by presence or absence of the said first input fluid jet, the binary value of the said other binary digit being represented by presence or absence of the said second input fluid jet, any "carry" signal to be carried into the said addition being represented by the presence of the said third input fluid jet, a plurality of output channels each positioned to receive a said output fluid jet directed in a

2

respective one of all the possible said directions, whereby presence of a said output fluid jet in any said output channel represents the sum of the said two digits as having the said one binary value, absence of a said output fluid jet in all said output channels represents the sum of the said two digits as having the said other binary value, and presence of a said output fluid jet having one of some only of the said output channels indicates a "carry" signal resulting from the said addition, means for detecting flowing of a said output fluid jet through any said output channel whereby to indicate the said sum, and means for detecting flowing of a said output fluid jet through any one of the said some only of the output channels whereby to indicate a "carry" signal resulting from the said addition.

A fluid logic element embodying the invention will now be described, by way of example, and with reference to the accompanying drawings, in which:

FIGURE 1 shows a diagrammatic representation of 20 the fluid logic element; and

FIGURE 2 shows a diagrammatic representation of means, for use with the logic element of FIGURE 1, for selecting, by use of low power jets, which of two paths a power jet should take.

FIGURE 1 shows diagrammatically a logic element comprising sources 6, 7 and 8 (shown diagrammatically) for producing three input fluid jets represented by the lines A, B and C. The three input jets have equal magnitude of momentum and act along the lines A, B and C respectively in the directions indicated by the arrows thereon so as to coincide at the common point D, the directions of the input jets being mutually perpendicular. The arrangement is such that any one jet can be on alone to the exclusion of the other two, any two of the jets 35 can be on to the exclusion of the other one, or all three jets can be on simultaneously. It will be appreciated that the input jet or jets reaching the point D produce a resultant output jet directed away from the point D through an interaction region E, in a direction depending 40 on the particular combination of the input jets existing at the time.

A solid block of material 9, generally cubical in shape but with one corner cut away to accommodate the interaction region E, defines seven output channels 10 to 16 each positioned so as to accept a particular one of all the possible resultant output jets. Output channel 10 is positioned so as to receive the resultant jet from the point D when only jet A is on; output channel 11 is positioned so as to receive the resultant jet from point D when only jet B is on; output channel 12 is positioned so as to receive the resultant jet from point D when only jet C is on; output channel 13 is positioned so as to receive the resultant jet from the point D when only the jets A and B are on; output channel 14 is positioned so as to receive the resultant jet from the point D when only the jets A and C are on; output channel 15 is positioned so as to receive the resultant jet from the point D when only the jets B and C are on; and output channel 16 is positioned so as to receive the resultant jet from the point D when all three jets A, B, and C are on simultaneously. It will be seen that channels 10, 11 and 12 respectively lie along three mutually perpendicular edges of the block 9, channels 13 and 14 lie along diagonals of two perpendicular sides of the block 55 9, channel 15 lies along the diagonal of the top of the block 9, while channel 16 lies along a diagonal through the block 9.

The fluid logic element illustrated can be utilised in a fluid data processing apparatus for summing two binary digits and at the same time taking into account a "carry" binary digit from the previous stage.

The table below shows an example of the utilisation of the fluid logic element as an intermediary stage in a fluid data processing apparatus. For this example two binary numbers are to be added, jet A representing the nth digit of one number, jet B representing the nth digit of the other number, and jet C representing "carry" data from the previous addition of all the less significant bits of the two numbers. A jet "on" represents a binary "1" and a jet "off" represents a binary "0." The table shows the "sum" and "carry" outputs resulting from the addition of all the possible combinations of inputs.

TABLE

Jets			"Sum"	Output Channel	"Carry"	Output Channel
C	B	A				
0	0	0	0	-----	0	-----
0	0	1	1	10	0	-----
0	1	0	1	11	0	-----
1	0	0	1	12	0	-----
0	1	1	0	-----	1	13
1	1	0	0	-----	1	15
1	0	1	0	-----	1	14
1	1	1	1	16	1	16

From this table, it will be seen that outputs representing the sum of the digits as being binary "1" in value can appear at any one of the channels 10, 11, 12 and 16, while outputs representing a "carry" can appear at any one of the channels 13, 14, 15 and 16. Therefore, the ends of the channels 10, 11, 12 and 16 remote from the point D are connected together (as shown by the chain-dotted lines) to form a common output channel 17, and the ends of the channels 13, 14, 15 and 16 are connected together (as shown by the chain-dotted lines) to form a common output channel 18. Issuance of a jet from the channel 17 therefore represents the sum of the digits as having the value of binary "1" while absence of such a jet represents the sum as having the value of binary "0," and issuance of a jet from the channel 18 represents a "carry" signal while absence of such a jet represents absence of a "carry" signal.

FIGURE 2 shows a source 20 arranged to direct a fluid power jet through an aperture in an arrangement 21 which has two output channels 21a and 21b. Further low-power sources 22 and 23 are positioned at apertures in the arrangement 21 so as to act respectively on opposite sides of a power jet produced by the source 20, the jet from source 22 tending to cause the power jet to pass along the channel 21a, and the jet from source 23 tending to cause the power jet to pass along channel 21b. The channels 17 and 18 (FIGURE 1) are respectively connected to two arrangements 21 so as to represent the respective sources 22 thereof. The sources 23 of the two arrangements 21 are arranged to be activated by control or inhibit means. Therefore, in the absence of jets from the sources 23 of the two arrangements, issuance of a jet from channel 17 (representing a binary "1" as the sum of the inputs) causes the jet from source 20 of one of the arrangements 21 to issue from channel 21a of the arrangement whence it may be further amplified or otherwise processed, while issuance of a jet from channel 18 (representing a "carry" signal) causes the jet from the source 20 of the other of the arrangements 21 to issue from the channel 21a of that arrangement whence, again, it may be further amplified or otherwise processed and may, for example, be arranged to constitute the jet C of a further device similar to that of FIGURE 1. In the absence of a jet from the channel 17 or 18, the jet from the source 20 of the appropriate arrangement 21 issues from the channel 21b of the arrangement and

may be allowed to pass to exhaust: the same happens when the sources 23 of the arrangements 21 are activated.

The embodiment shows a fluid logic element which is capable of carrying out two logical functions, that is, the summing of two binary bits as well as the taking into account of a "carry," using only one jet interaction region E. Hence the time taken to perform such an operation is reduced.

Although three mutually perpendicular and equal momentum jets are utilised in the embodiment described, the invention should not be considered to be limited in this way. The three jets need not be mutually perpendicular, there may be more than three jets, and the magnitude of momentum of all the jets need not be the same. In any particular arrangement, the output channels would be arranged according to the number of jets and their respective momentums.

I claim:

1. A fluid logic element including means defining three mutually perpendicular fluid jet paths directed towards a single point in space,

means for passing an input fluid jet along each said path whereby to produce an output fluid jet directed away from the said point in an outward direction which depends on the particular combination of said input fluid jets existing at the time, and means defining a plurality of output channels each positioned to receive a said output fluid jet having a respective one of all possible said outward directions,

the said means defining the said output channels being a substantially cubical piece of material with one corner cut away, the cubical piece of material being positioned so that the said single point is substantially co-incident with the position previously occupied by the said one corner, three of the said output channels being defined in the cubical piece of material so as substantially to lie respectively along the three edges of the cubical piece of material whose projections meet at the said single point, three further said output channels being defined in the cubical piece of material so as substantially to lie respectively along diagonals of three faces of the cubical piece of material which diagonals have projections meeting at the said single point, and another said output channel being defined in the cubical piece of material so as substantially to lie along the diagonal through the cubical piece of material whose projection intersects the said single point.

2. Fluid logic apparatus for performing binary addition of a first and a second binary digit, comprising means defining three fluid jet paths directed towards a single point in space in respectively different predetermined inward directions which do not all lie in the same plane;

input means for passing an input fluid jet along each said path whereby to produce an output fluid jet directed away from the said point in an outward direction which depends on the particular combination of said input fluid jets existing at the time, said input means comprising

first means for passing along said first path an input fluid jet whose presence represents one binary value of said binary digit and whose absence represents the other binary value thereof, second means for passing along said second path an input fluid jet whose presence represents the binary value of said second binary digit and whose absence represents the other binary value thereof, and

third means for passing along said third fluid jet path an input fluid jet representing any "carry" to be carried into said addition; means defining first, second, and third output channels respectively positioned parallel to and colinear with

the three fluid jet paths whereby each output channel receives the said output fluid jet produced when a respective one of the input fluid jets is present alone;

means defining fourth, fifth, and sixth output channels, the fourth output channel being co-planar with and lying between the first and second output channels, the fifth output channel being co-planar with and lying between the first and third output channels, and the sixth output channel being co-planar with and lying between the second and third output channels, each of the fourth, fifth, and sixth output channels receiving the said output fluid jet produced when a respective pair of the input fluid jets is present to the exclusion of the remaining input fluid jet;

means defining a seventh output channel positioned for receiving the output fluid jet produced when all the input fluid jets are present at the same time;

a first common channel;

means connecting the first, second, third and seventh output channels to discharge into the first common channel the presence or absence of the said output jet wherein represents the binary sum of the said two digits;

a second common channel; and

5

10

25

means connecting the fourth, fifth, sixth, and seventh output channels to discharge into the second common channel presence or absence of the said output jet wherein represents a "carry" produced by the said addition.

3. Apparatus according to claim 2, in which the said fluid jet paths are mutually perpendicular.

4. Apparatus according to claim 2, in which the magnitude of the momentum of each said input fluid jet is the same.
